DUAL FIRING RATE OIL BURNER

Richard M. Cochrane, West Springfield, Mass., assignor to Gilbert & Barker Manufacturing Company, West Springfield, Mass., a corporation of Massachusetts

Application October 23, 1947, Serial No. 781,600

10 Claims. (Cl. 158—28)

1

This invention relates to improvements in oil burners of the intermittently-operated type, such as are used for house heating service, wherein two oil-atomizing nozzles are employed and are adapted for operation alternately.

The invention has for an object the provision, in a burner of this type, in which one nozzle is selected for operation and operates intermittently on and off in cycles while another nozzle ordinarily remains idle, of improvements which provide for the automatic operation of the unselected nozzle at the end of each cycle of operation of the burner, whereby to purge the unselected nozzle of the hot oil which it contains and keep the nozzle in better condition so that carbonization and consequent stoppage of the idle nozzle is less liable to occur.

The invention has for another object the provision in a burner of the kind described of improved means automatically operable in the emergency that the nozzle, which is selected for operation, fails to operate, to connect the other nozzle for operation in its place.

The two nozzles, referred to, generally have different firing rates to provide for operation of the burner at high or low rates, as may be selected manually or automatically by any suitable controlling means, as changes in the weather occur.

These and other objects and advantages will best be understood in connection with the description of one illustrative example of the invention in the accompanying drawings, in which:

Fig. 1 is a top plan view of an oil burner embodying the invention;

Fig. 2 is a diagrammatical view of the oil supply system for the burner including also the means for controlling the air supply to the burner;

Fig. 3 is a wiring diagram showing the electrical control system of the burner; and

Figs. 4 and 5 are wiring diagrams illustrating modifications in the electrical control system of the burner.

Referring to these drawings; there is shown in Fig. 1 a burner of the so-called gun type, wherein air is supplied by a fan 1, located in a housing 2, to an air conduit 3 having an open end 4, adapted to be inserted into the fire box of a heating apparatus. The rear end of conduit 3 is closed. The fan 1 is driven by direct connection to the shaft 5 of an electric motor 6, fastened to one side of the fan housing 2.

Located in the air conduit 3, near the outlet end thereof, are two oil atomizing nozzles 7 and 8, which are adapted for connection one at a time to an oil supply pump 9 in a manner later

2

to be described. Each nozzle will produce a substantially conical fog-like spray of oil to mix with the air supplied through conduit 3. The air and oil mixture will be suitably ignited, as by the spark electrodes 10. Preferably, each nozzle is of the pressure atomizing type. The nozzles 7 and 8 may have different capacities. As a single illustrative example, the nozzle 7 may have a capacity of one gallon per hour and the nozzle 8 may have a capacity of one and one half gallons an hour, both at a pressure of say 100 pounds per square inch.

The oil pump 9 is fixed as indicated to the cross bar portion 11 of a yoke, the legs 12 of which are integrally connected to the fan housing 2. This pump is driven by the motor 6, preferably through the intermediary of a speed-responsive clutch, the driving and driven elements of which are respectively indicated at 13 and 14. As shown, the shaft 15 of the pump is connected to the driven element 14 of the clutch and the driving element 13 of the clutch is connected by a shaft 16 and a flexible coupling 17 to the hub of fan 1. The arrangement is substantially like that shown in the Logan Patent No. 1,985,934, granted January 1, 1935, and enables the motor and fan to acquire considerable speed before the oil pump is started and enables the pump to be stopped before the fan, for the purposes set forth fully in said patent.

The air inlet in the fan housing 2 is shown at 18. It is controlled by an annular shutter 19, the central opening of which receives the clutch elements 13 and 14, as best shown in Fig. 2. The shutter is supported by a screw 20, on which it is threaded, and this screw has smooth cylindrical portions, one near each end thereof, which are slidably and rotatably mounted, one in a bearing 21 in housing 2 and the other in a bearing 22 in the cross bar 11. The screw 20 is bodily movable in the direction of its axis to carry the shutter 19 from a position suitable for high firing rate operation to a position suitable for low firing rate operation and vice versa. The screw 20 has a shoulder 23 which is adapted to abut the adjacent end face of bearing 21 and limit the axially inward movement of the screw and thus define the low firing rate position of the shutter. Such position may be varied by rotating screw 20. Sliding movement of the screw in the opposite direction is limited by a second screw 24, with the inner end of which a circumferentially grooved collar 25, fixed to screw 20, is adapted to abut and define the high firing rate position 55 of the shutter. The screw 24 is threaded into a

circular end housing 26, secured to the cross bar 11. By turning screw 24, the high firing rate position of the shutter may be adjusted. A part-cylindrical member 27 encloses the space between the member 26 and housing 2, except for suitable openings to enable air to enter and reach the inlet 18.

The air shutter 19 is shifted from one position to another by means of a lever 28, fulcrumed near its lower end at 29 and having its upper end engaged in the groove in collar 25. The lower end of this lever is pivotally connected to the outer end of a piston rod 30, the inner end of which carries a piston 31, slidably mounted in a cylinder 32. The inner end of this cylinder is closed and the piston is held in abutment with this closed end by means of a spring 33, coiled around rod 30 and acting between the outer face of piston 31 and a head 34, which is threaded into the outer end of the cylinder and slidably supports the piston rod. When the burner is not in operation the shutter is held in high firing rate position by spring 33. When the burner is operating at the high firing rate the shutter is held in the same manner and in the same and illustrated position. When the burner is to operate at the low firing rate, oil is admitted to the inner end of cylinder 32 and the piston 31 is moved outwardly, rocking lever 28 clockwise and moving screw 29 until the shoulder 23 abuts the adjacent end face of bearing 21, thus carrying the shutter 19 into position for low firing rate operation and holding the shutter in such position.

The oil pump 9 includes a combined cut-off and pressure-regulating valve housed within the pump casing. This valve is shown diagrammatically by a piston 35, pressed by a spring 35' against a seat 36, through which the pump outlet passage 37 extends. Oil drawn into the pump from a suction pipe 38 is forced by the pump into a chamber 39 and, when the oil reaches a predetermined minimum pressure, say 85 pounds per square inch, the piston 35 is moved to the left away from seat 36, allowing oil to enter the outlet 37 and flow to one or the other of the nozzles 7 and 8 in a manner later to be described. When the oil in chamber 39 reaches a maximum predetermined pressure, say 100 pounds per square inch, piston 35 will be moved to the left far enough to uncover a port 40 and allow oil from chamber 39 to flow through port 40 into a chamber 41 which is connected to the suction side of the pump. An example of one pump suitable for the purpose will be found in Wahlmark Patent No. 2,232,983, dated February 25, 1941, to which reference is made for a complete disclosure of the pump structure with its cut-off and pressure-regulating or by-pass valves, if necessary or desired.

The flow of oil from the pump to the nozzles 7 and 8 is respectively controlled by two valves 42 and 43. The valve 42 is located within a tube 44 of non-magnetic material and is normally held by means of a spring 45 in the illustrated position against a seat 46 to close the outlet to a pipe 47 which extends to nozzle 7. A solenoid 48 surrounds tube 44 and is arranged in a casing 45 of magnetic material. When solenoid 48 is energized, it lifts valve 42 until it engages a seat 49 in the upper part of casing 45 and closes an outlet, which is connected to a pipe 50, leading to the suction side of pump 9, as to pipe 38. The valve 43 is located in a non-magnetic tube 51 and is held by a spring 52 against a seat 53 to close an outlet which is connected by a pipe 54 to nozzle

8. A solenoid 55 surrounds tube 51 and is located in a magnetic casing 56. When energized, the solenoid 55 raises valve 43 allowing oil to flow through pipe 54 to nozzle 8 and moves it against a seat 57 to close an outlet which is connected to a pipe 58. Pipe 58 has a branch 59 leading to the inner end of cylinder 32 and a branch 60 leading to the space within tube 44. A pipe 61 leads from the outlet 37 of pump 9 to the space within tube 51.

The solenoid valves have been shown merely in diagrammatical form. These valves are standard commercial articles, which can be bought in the market, and complete illustration and description of them is therefore deemed unnecessary.

When the low rate nozzle 7 is to be operated, the solenoid 48 is energized and the solenoid 55 remains deenergized. The valve 42 is raised to engage seat 49 while the valve 43 remains, as illustrated, engaged with seat 53. The pump 9 will force oil through pipe 61 into tube 51 and thence through pipes 58 and 60 into tube 44 and thence through pipe 47 to nozzle 7. The raised valve 42 closes the outlet to pipe 50 and thus disconnects the cylinder 32 from the suction of pump 9. Oil from the pump flowing into pipe 58 as described will also flow into the inner end of cylinder 32 and move piston 31 outwardly to shift the shutter 19 into low firing rate position. The closed valve 43 prevents oil from flowing to the high rate nozzle 8.

When high firing rate operation is desired, the solenoid 55 is energized and the solenoid 48 remains deenergized. Accordingly valve 43 is raised to engage seat 57 and valve 42 remains engaged with seat 46 as illustrated. Oil from pump 9 will then flow through pipe 61 into tube 51 and from the latter through pipe 54 to the high rate nozzle 8. Oil cannot pass to the cylinder 32 or tube 44 because the valve 43 engages seat 57. The lowered valve 42 closes the outlet to the nozzle 7 and enables cylinder 32 to communicate with the suction side of pump 9 by way of pipes 59 and 60, tube 44 and pipes 50 and 38. Accordingly, the piston will be moved to the illustrated position for high rate firing.

The burner is controlled by a room thermostat switch, which responds to the temperature in the space to be heated and starts and stops the motor 6 and the ignition means in the usual or any suitable way. A single illustrative example of one control system suitable for the purpose is shown in Fig. 3. The motor 6 and the primary 62 of an ignition transformer are connected in parallel to the wires 63 and 64, which are connected to the terminals 65 and 66, respectively, of a control instrument. A third terminal 67 of such instrument is connected by a wire 68 to the contact of a switch 69, which in turn is connected by a wire 70 to the terminal 65. The supply wires 71 and 72 of a suitable source of alternating current are connected to the terminals 67 and 66, respectively. The secondary 73 of the ignition transformer is connected by wires 74 to the described ignition electrodes 10. On a demand for heat from the burner, the switch 69 is closed by the action of a room thermostat switch 75 in a manner to be later described and a circuit is closed to the motor 6 and primary 62 of the ignition transformer. Starting from the supply terminal 67, this circuit is as follows; wire 68, closed switch 69, wire 70, terminal 65, wire 63, the motor 6 and primary 62, and wire 64 to the other supply terminal 66.

75 The solenoids 48 and 55 are controlled by a se-

lector switch 76, which may be actuated manually or automatically as desired. As shown diagrammatically, this selector switch is operated by a thermostat 77 which may be placed at various locations as desired. For example, the thermostat 77 may be located outdoors and be arranged to move the selector switch to high firing rate position, when the outdoor temperature is at 20° Fahr. or below, and to move the switch to low firing rate position, when the outdoor temperature is above 20° Fahr. The switch 76 is shown in high firing rate position. This switch includes a tube 78, tiltable by thermostat 77 and having one pair of terminals 79 and 80 adapted to be connected by the mercury 81 in the tube when the latter is in the illustrated position and a second pair of terminals 82 and 83, adapted to be connected by the mercury, when the tube is tilted to its other position. The terminals 80 and 82 are interconnected as shown.

The energizing circuit for the solenoid 55 includes a wire 84 which connects terminal 65 to the interconnected terminals 80 and 82 of the selector switch; a wire 85, which connects the terminal 79 of such switch to a terminal 86; a wire 87 connecting the latter to a switch 88, which has a contact 89, a wire 90 connecting this contact to a heat-actuated time switch 91, having a contact 92, a wire 93 connecting such contact to one terminal of solenoid 55, and wires 94 and 95 which connect the other terminal of solenoid 55 to terminal 66. On a demand for heat from the burner the switch 69 closes, as described, to start the motor 6 and ignition means and it also closes a circuit to that solenoid which is selected by selector switch 76, in this case the solenoid 55. The circuit is as follows, from supply terminal 67, wire 68, closed switch 69, wire 70, terminal 65, wire 84, terminal 80, mercury 81, terminal 79, wire 85, terminal 86, wire 87, switch 88, contact 89, wire 90, switch 91, contact 92, wire 93, solenoid 55, and wires 94 and 95 to the other supply terminal 66.

The energizing circuit for solenoid 48 is the same as for solenoid 55, through wire 84 and then includes the terminals 82 and 83, a wire 96 connecting terminal 83 to a terminal 97, a wire 98 connecting the latter to a switch 99 having a contact 100, a wire 101 connecting such contact to a heat-actuated time switch 102, having a contact 103, a wire 104 connecting the latter to one terminal of solenoid 48 and a wire 105 connecting the other terminal of this solenoid to wire 95. Assuming that the switch 76 is tilted to its other position, on a demand for heat from the burner, switch 69 will close a circuit to solenoid 48 as follows; from supply terminal 67, wire 68, closed switch 69, wire 70, terminal 65, wire 84, terminal 82, mercury 81, terminal 83, wire 96, terminal 97, wire 98, switch 99, contact 100, wire 101, switch 102, contact 103, wire 104, solenoid 48, wires 105 and 95, to the other supply terminal 66.

The described switch 69 is actuated by a relay including a coil 106. This relay also actuates three other switches 107, 108 and 109, the blades of which are interconnected by the conductor 110. The relay coil 106 is in a low voltage circuit supplied by the secondary 111 of a transformer, the primary 112 of which is connected by wires 113 and 114 to the supply terminals 66 and 67, respectively. This low voltage circuit is controlled by room thermostat 75. The latter includes a bi-metallic blade 115, two fixed contacts 116 and 117, which are engaged successive-

ly by the blade in the order named on a demand for heat, and an electric heating coil 118 which at certain times is energized to heat blade 115 and expedite its switch opening movement. The contacts 116 and 117 are connected by wires 119 and 120 to terminals 121 and 122, respectively. The blade 115 is connected by a wire 123 to one terminal of heater 118 and the other terminal of the latter is connected by a wire 124 to a terminal 125. The terminal 121 is connected by a wire 126 to one terminal of secondary 111 and the other terminal of the latter is connected by a wire 127 to one terminal of relay coil 106. The other terminal of the latter is connected by a wire 128 to the contact of a heat-actuated time switch 129, which is connected by a wire 130 to one terminal of the electric heating coil 131 that actuates it. The other terminal of coil 131 is connected by a wire 132 to one of a pair of closed contacts 133, the other of which is connected by a wire 134 to one of a pair of separated contacts 135 and by a wire 136 to the contact of switch 107. The other contact 135 is connected by a wire 137 to switch 129. The contact 133, which is connected to wire 134, is also connected to one of a second pair of contacts 138 and the other contact 138 of such pair is connected by wires 139 and 140 to the terminal 122. The switch 108 has its contact connected by a wire 141 to wire 140. The switch 109 has its contact connected by a wire 142 to one terminal of the electric heating coil 143 of a heat-actuated switch 144 and the other terminal of coil 143 is connected by a wire 145 to terminal 125. A relay is provided for actuating the described switches 88 and 99 and one terminal of its coil 146 is connected by a wire 147 to one terminal of switch 144 and the other terminal of the latter is connected by a wire 148 to wire 127. The other terminal of coil 146 is connected by a wire 149 to wire 126. The pairs of contacts 133, 135 and 138 are actuated by a stack thermostat, conventionally shown at 150, together with two other pairs of contacts, which for the present may be disregarded. When combustion occurs, the thermostat 150 will first cause the contacts 135 to engage after which the contacts 138 will be caused to separate and finally the contacts 133 will be caused to separate.

On a demand for heat from the burner, the room thermostat switch 75 closes, its blade 115 making contact first with the contact 116 and then with the contact 117. As soon as both contacts are engaged by the blade, a starting circuit is closed to relay 106, as follows; from the right hand terminal of secondary 111, by wire 126, terminal 121, wire 119, contact 116, blade 115, contact 117, wire 120, terminal 122, wires 140 and 139, engaged pairs of contacts 138 and 133, wire 132, heating coil 131, wire 130, closed switch 129, wire 128, relay coil 106 and wire 127 to the left hand terminal of the secondary 111. The relay pulls in closing switch 69 to start the burner and ignition means, as heretofore described, and also closing switches 107, 108 and 109.

The last three switches prepare alternate circuits for the relay coil 106, which circuits are subsequently brought into play after the contacts 135 engage, following occurrence of combustion. When the contacts 135 engage, the heating coil 131 is shunted out, the shunt being as follows, from the right hand terminal of coil 131, by wires 130 and 137, engaged contacts 135, wire 134, engaged contacts 133 and wire 132 to the left hand terminal of coil 131. If combustion occurs within the time interval, say 90 seconds,

which it takes for coil 131 to heat switch 129 sufficiently to open it, the coil 131 is shunted out to prevent the switch from opening. If combustion does not occur within said interval, switch 129 will open, causing relay 106 to drop out and open the several switches controlled by it, thereby stopping the burner. Manual resetting of switch 129 is necessary before the burner can again operate.

Assuming that combustion has occurred and that contacts 135 have engaged, the circuit to relay coil 106 now includes a parallel branch which starts from the left hand end of wire 140 and extends through wire 141, closed switch 108, the conductor 110 to switch 107, closed switch 107, wire 136, that part of wire 134 which leads to right hand contact 138, engaged contacts 135, and wire 137 to switch 129. The other branch from switch 129, which includes coil 131 and wires 130, 132 and 134 will be broken, when the contacts 138 separate, shortly following the engagement of contacts 135. The burner now operates on a holding circuit controlled by the contacts 135 so that on a failure of combustion, the burner may be stopped very quickly by the first drop in temperature of the stack thermostat 150.

At the same time that the described branch in the circuit to relay coil 106 was closed, another branch was closed through switch 109, wire 142, heating coil 143, wire 145, terminal 125, wire 124, heating coil 118, wire 123 and blade 115 to contact 117. This last-named branch has considerable resistance and no substantial current flows through it because of the then existing low resistance shunt comprising wire 120, terminal 122, wires 140 and 141 and closed switch 108. However, after a demand for heat has been nearly satisfied, the blade 115 moves away from contact 117, while remaining for a while (say from 2 to 5 minutes) engaged with contact 116. Then, the only circuit to coil 106 is through the last-named branch, which includes coil 118, and the latter heats up the blade 115 and accelerates its opening movement, causing it to disengage from contact 116 earlier than it otherwise would for the purpose of avoiding over run of temperature. When the blade 115 leaves contact 116, the relay 106 drops out, causing the burner to stop. The stack thermostat 150 cools, causing the contacts 135 to separate and subsequently causing the contacts 138 and then the contacts 133 to reengage. The time between the opening of contacts 135 and the engagement of contacts 133 is about 60 seconds.

Whenever the burner stops due to failure of combustion and the opening of contacts 135, the one minute interval between such opening and the closing of contacts 133 affords a scavenging period. With the room thermostat still closed, the burner will start up, when the contacts 133 and 138 have been engaged, through the starting circuit, above described, which circuit includes the heating coil 131. Then, if the combustion failure continues, for say 90 seconds, the switch 129 will open and stop the burner, preventing further operation of it until switch 129 is manually reset.

The control system described, insofar as it affects the operation of relay 106 and thus the burner control switch 69, is old and well known and has been described herein merely so that the application to it of the improvements of this invention and the operation of such improvements will be understood.

One purpose of this invention is to provide for the operation of the nozzle, which is not selected for operation by switch 76, once during each cycle of operation of the burner and at the end of each such cycle. The oil in the unselected nozzle that has been heated up during the operation of the selected nozzle, is ejected from the unselected nozzle just prior to the stopping of the burner. The unselected nozzle is purged of hot oil and left filled with relatively cool oil when the burner stops. Carbonization of the unselected nozzle is much less liable to occur.

The purging of the unselected nozzle is effected by the described switches 88 or 99, as the case may be, when these switches are moved by relay 146 into engagement with contacts 151 and 152, respectively. The contact 151 of switch 88 is connected by a wire 153 to the wire 101 which connects with contact 100 of switch 99. Accordingly, when switch 88 moves away from contact 89, the normal energizing circuit theretofore existing to solenoid 55 is broken and, when switch 88 engages contact 151, a circuit to the low firing rate solenoid 48 is closed. The last-named circuit is as follows; from supply terminal 61, wire 68, closed switch 69, wire 70, terminal 65, wire 84, terminal 80, mercury 81, terminal 79, wire 85, terminal 86, wire 87, switch 88, contact 151, wires 153 and 101, switch 102, contact 103, wire 104, solenoid 48, wires 105 and 95 to supply terminal 66. Thus, the low firing rate nozzle will be operated on the closing of switch 88, whenever selector switch 76 is set as shown for high firing rate operation. The closing of switch 99 at such time has no effect because the terminals 82 and 83 of the selector switch are not connected.

If the selector switch is set for low firing rate operation, then the terminals 82 and 83 will be connected by mercury 81 and the terminals 79 and 80 will be disconnected. The normal energizing circuit to solenoid 48 will be broken when switch 99 leaves contact 100 and, when this switch engages its contact 152, which is connected to contact 89 of switch 88, a circuit to solenoid 55 will be closed. This last-named circuit may be traced as follows, from supply terminal 61, by wire 68, closed switch 69, wire 70, terminal 65, wire 84, terminal 82, mercury 81, terminal 83, wire 96, terminal 97, wire 98, switch 99, contact 152, wire 90, switch 91, contact 92, wire 93, solenoid 55 and wires 94 and 95 back to supply terminal 66. The high firing rate nozzle 3 will thus be operated on the closing of switch 99, whenever the selector switch 76 is set for low firing rate operation. The closing of switch 88, at such time, has no effect because the terminals 79 and 80 of the selector switch 76 are not connected.

The operation of the relay 146 occurs at the end of each cycle of operation of the burner. As heretofore described, substantially no current flows in that branch of the circuit to relay 106 that includes the heating coils 143 and 118 because of the shunt, comprising closed switch 108, wires 141 and 140, terminal 122, wire 120, contact 117, blade 115 and wire 123. This shunt is broken when the blade 115 on rising temperature, disengages from contact 117. For a short interval current flows through coils 143 and 118 and the former will in say 60 seconds cause switch 144 to close and energize relay 146 through the circuit from the secondary 111, which includes wire 126 as far as wire 149, wire 149, relay 146, wire 147, closed switch 144, and wires 148 and 127. The relay 146 pulls in so that switches 88 and 99

are moved as described to cause the nozzle, which is not selected by switch 76, to operate. As soon as blade 115 leaves contact 116, to stop the burner, relay 146 drops out and switches 88 and 99 move back to their illustrated positions.

The invention also provides means whereby if one nozzle becomes inoperative, the other nozzle may be used in its place. Such means include the time switches 91 and 102 and certain other devices soon to be described. The switch 91 has an electric heating coil 154, which when energized for say 30 seconds will move it away from contact 92 into engagement with a contact 155, which is connected by a wire 156 to the switch 102. Thus, the solenoid 55 may be disconnected from the supply and the solenoid 48 connected to such supply in its place. The switch 102 has an electric heating coil 157 which when energized for say 30 seconds will move away from contact 103 and engage a contact 158, which is connected by a wire 159 to switch 91. Thus the solenoid 48 may be disconnected from the supply and the solenoid 55 connected to such supply in its place. The heating coils 154 and 157 have energizing circuits, which are the same as the normal energizing circuits to solenoids 55 and 48, respectively, up to the switches 91 and 102, respectively. The energizing circuit for coil 154 then extends through such coil, a wire 160, a pair of engaged contacts 161 and wires 162 and 163 to the supply terminal 66. The energizing circuit for coil 157 extends from switch 102 through coil 157 and thence by a wire 164, a pair of engaged contacts 165, and wires 166 and 163 to supply terminal 66. The time switches 91 and 102, when actuated by their respective heat coils, are locked out by suitable spring-actuated latches 167 and 168, respectively, which require manual resetting before the time switches can again assume their normal and illustrated positions. The pairs of contacts 161 and 165 are adapted to be actuated by the stack thermostat 150 so as to be engaged, as shown, when the burner is idle and during the starting interval of the burner until after combustion has been established, when they open to disconnect their respective heating coils from the supply. Such disconnection occurs in say five seconds following the occurrence of combustion.

In operation, with the selector switch set as shown for high firing rate operation, on a demand for heat, the room thermostat 75 will close a circuit to relay 106 and start the burner as described. The solenoid 55 will initially be energized to connect the high rate nozzle 8 for operation. At the same time, the heating coil 154 will be energized to heat switch 91. If now the nozzle 8 is inoperative, the heater 154 will in 30 seconds move switch 91 to engage contact 155 and the switch 91 will be locked by latch 167 in this position. The switch 91, when engaging contact 155, closes an emergency energizing circuit to the solenoid 48. Such circuit is the same as the normal energizing circuit through switch 91 and then extends to contact 155, wire 156, switch 102, contact 103, wire 104, solenoid 48, and wires 105 and 95 to supply terminal 66. Thus, the solenoid 48 may be energized to connect nozzle 7 to operate in place of the selected nozzle 8. If the nozzle 7 operates and combustion occurs, the stack thermostat 150, in addition to the other functions heretofore described, causes the pairs of contacts 161 and 165 to separate and deenergize the heating coils 154 and 157 respectively.

Assuming now that the selector switch 76 is set for low firing rate operation and that the 76 respectively connected by wires 170 and 171 to

nozzle 7 is inoperative, when the burner starts on closing of switch 69, the solenoid 48 is initially energized through its normal energizing circuit, heretofore described, and current flows through heating coil 157. In say 30 seconds, the switch 102 will be moved to engage contact 158 and the latch 168 will lock the switch in this position. When in such position, this switch closes an emergency energizing circuit to the solenoid 55, which circuit is the same as the normal energizing circuit described through switch 102 and then extends by contact 158, wire 159, switch 91, contact 92, wire 93, solenoid 55 and wires 94 and 95 to the supply terminal 66. Thus, the solenoid 55 will be energized to connect the high firing rate nozzle 8 for operation. If this nozzle operates and combustion occurs, the stack thermostat 150 will separate the pairs of contacts 161 and 165 and the heating coils 154 and 157 will be deenergized.

Whenever either time switch 91 or 102 has been actuated to engage contacts 155 or 158, respectively, the subsequent operation of the switches 88 and 99 at the end of the cycle of burner operation will have no effect. Each time switch, when actuated as described, makes a connection from the normal energizing circuit of one solenoid to the normal energizing circuit of the other solenoid and the switches 88 and 99, when moved to their respective contacts 151 and 152, do the same thing. Therefore, the nozzle-purging action does not take place, when one nozzle has already failed to operate.

In the event that both nozzles are inoperative, when the burner is started, the two time switches will be successively actuated into lock out position by their heating coils and the circuit to both solenoids will be broken by the switches disengaging from the contacts 92 and 103. The engagement of these switches with the contacts 155 and 158 will not then establish any circuits. There will be no combustion and in 90 seconds the heating coil 131 will open switch 129 and stop the burner. Manual resetting of switches 129, 91 and 102 will be required before the burner can again be operated.

As long as both nozzles are operative, actuation of the time switches 91 and 102 will not occur because their heating coils will be disconnected by the opening of the pairs of contacts 161 and 165 in say five seconds and in much less time than is required for the heating coils to actuate their switches.

If the emergency feature of switching from one nozzle to another in case one of them becomes inoperative is not desired, the two time switches 91 and 102 with their heating coils 154 and 157 and latches 167 and 168 and the pairs of contacts 161 and 165 may be eliminated together with wires 156, 159, 160, 162, 163 and 164. The wire 90 may then be connected to wire 93 and the wire 101 may then be connected to the wire 104. The nozzle-purging feature of the invention will then operate in the same way as heretofore described.

The relay coil 146 may, if desired, be included directly in the circuit which includes the thermostat heater 118. Such an arrangement is shown in Fig. 4. Only a portion of the control system has been shown sufficient to show the changes that have been made over Fig. 3. It is to be understood that all the elements and connections of Fig. 3 not shown in Fig. 4 are to be used. As shown in Fig. 4, the terminals of coil 146 are respectively connected by wires 170 and 171 to

terminal 125 and the contact of switch 109. The heat-actuated switch 144 with its coil 143 and connections are omitted. As long as blade 115 engages contact 117, no current flows through relay 146 because of the shunt, comprising connection 110, closed switch 108, wires 141 and 140, terminal 122, wire 120 and contact 117. When blade 115 leaves contact 117, this shunt is broken and all the current flows through relay 146, causing it to actuate switches 88 and 99, as heretofore described. With this arrangement, the coils 106 and 146 and heater 118 must be specially designed so that the relay 146 will actuate its switches, when placed in series with relay 106, and so that the relay 106 will not drop out when relay 146 is placed in series with it.

Fig. 5 shows a slight modification of the Fig. 3 arrangement. As in Fig. 4, only enough of the diagram of Fig. 3 has been repeated to show the change but it is understood that the diagram of Fig. 3 will be used. The relay 146 is controlled by a heat-actuated time switch 144 as before but the right hand terminal of the relay coil is connected by a wire 172 to wire 145 instead of to wire 126, as in Fig. 3. When the switch 144 closes, the relay coil 146 will be in one branch of a divided circuit and the heater 118 will be in the other branch, the circuit including, of course, the thermostat heater 118. The resistance of the circuit to this heater will be less after switch 144 closes than it was before. Accordingly, more current will flow through heater 118 after switch 144 closes than before and the heater will cause blade 115 to disengage from contact 117 earlier than it otherwise would.

The invention has been described as adapted for use with a room thermostat of the anticipating type, having an electric heating coil such as 118, because it is contemplated that the invention will be more likely to be used with a control instrument of this standard type. However, the room thermostat heater, such as 118, is not essential to the invention, according to its broader features. It will be clear from an inspection of Figs. 3, 4, or 5 that the system will operate if this heating coil 118 is omitted. In Figs. 3 and 5, assuming that coil 118 is omitted, and the wires 123 and 124 are connected together, there still exists a divided circuit having one branch of high resistance, which comprises switch 109, wire 142, heating coil 143, wire 145, terminal 125, wires 124 and 123 and blade 115, shunted out by a low resistance branch, which comprises the switch 108, wires 141 and 140, terminal 122, wire 120 and contact 117. Thus, the branch with coil 143 carries substantially no current until blade 115 leaves contact 117, when it carries all the current, whereby the coil is energized and in 60 seconds will close switch 144, causing relay 146 to be energized to actuate switches 88 and 99, to effect the purging of the unselected oil atomizing nozzle at the end of a cycle of operation of the burner. The same result will be effected in Fig. 4, the only difference being that the high resistance branch includes the relay coil 146 instead of the time switch 144. With the elimination of the heater 118, the period of operation of the unselected nozzle will be longer.

The invention is directed to keeping the unselected nozzle of a dual nozzle burner in as good condition as possible in order to guard against the carbonizing and eventual stoppage of such nozzle which might otherwise occur if this nozzle should be idle for long periods while subjected to the heat of combustion resulting from the oil fed

from the other and selected nozzle. The invention is based generally on operating the unselected nozzle for a brief period during each cycle of operation of the burner. The maximum value from this plan of operation is secured when the brief period of operation of the unselected nozzle occurs at the end of the cycle of burner operation so that the oil in the nozzle which has been heated up during the operation of the other nozzle is eliminated and replaced by relatively cool oil.

I claim:

1. A dual nozzle oil burner apparatus for house heating systems, having in combination, an air supply fan, an oil supply pump, a motor for driving the fan and pump, an air conduit connected to receive air from the fan, a pair of oil conduits extending within the air conduit, an atomizing nozzle on one end of each oil conduit, valve means for selectively connecting said oil conduits to said pump, means for starting and stopping said motor to produce a cycle of operation of the burner, and means controlled by said last-named means and automatically operable near the end of each cycle of operation of the burner to stop the flow of oil through the selected oil conduit and nozzle and supply oil to the other oil conduit and nozzle.

2. A dual nozzle oil burner apparatus for house heating systems, having in combination, an air supply fan, an oil supply pump, a motor for driving the fan and pump, an air conduit connected to receive air from the fan, a pair of oil conduits extending within the air conduit, an atomizing nozzle on one end of each oil conduit, valve means for selectively connecting said oil conduits to said pump, means for starting and stopping said motor to produce a cycle of operation of the burner, and means controlled by said last-named means and for automatically operating said valve means near the end of each cycle of operation of the burner to stop the flow of oil through the selected oil conduit and nozzle and supply oil to the other oil conduit and nozzle.

3. A dual nozzle oil burner apparatus for house heating systems, having in combination, an air supply fan, an oil supply pump, a motor for driving the fan and pump and adapted to be started and stopped under the control of a room thermostat switch to produce a cycle of operation of the burner, an air conduit connected to receive air from the fan, a pair of oil conduits extending within the air conduit, an atomizing nozzle on one end of each conduit, valve means for selectively connecting said oil conduits to said pump, and electrically operated means adapted to be controlled by the room thermostat switch and operable for a brief period, just prior to the opening of such switch to stop the motor, to stop the flow of oil through the selected oil conduit and nozzle and supply oil to the other oil conduit and nozzle.

4. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump and adapted to be started and stopped by a room thermostat switch to produce a cycle of operation of the burner, ignition means for igniting the air and oil mixture, electromagnetically operated valve means for selectively connecting said oil conduits to said pump, and a selector switch in circuit with such means and movable from one

position to another to cause the connection of one or the other of said oil conduits to the pump; switching means in circuit with the selector switch and electromagnetically-operated valve means and movable from a normal position to a second position to cause a reversal of action of said means, whereby the oil conduit and nozzle not selected by the selector switch is connected to the pump in place of the selected oil conduit and nozzle, electrical means operable when energized and deenergized to move said switching means to its second position and normal position respectively, said room thermostat switch including a thermostatic blade movable responsive to room temperature and two contacts both engaged by the blade during most of each cycle of operation of the burner, said blade on rising temperature disengaging from one of said contacts before the other, said electrical means including an element of substantial resistance and an energizing circuit including said element and blade, and a low resistance shunt across said element and blade including the contact from which the blade first disengages, whereby current flow through the electrical means is diverted until near the end of the cycle of burner operation.

5. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump and adapted to be started and stopped by a room thermostat switch to produce a cycle of operation of the burner, ignition means for igniting the air and oil mixture, electromagnetically-operated valve means for selectively connecting said oil conduits to said pump, and a selector switch in circuit with such means and movable from one position to another to cause the connection of one or the other of said oil conduits to the pump, switching means in circuit with the selector switch and electromagnetically-operated valve means and movable from a normal position to a second position to cause a reversal of action of said means, whereby the oil conduit and nozzle not selected by the selector switch is connected to the pump in place of the selected oil conduit and nozzle, a relay operable when energized and deenergized to move said switching means to its second position and normal position respectively, an energizing circuit for said relay including a switch heat-actuated to closed position, an electric heating element for actuating said switch, an energizing circuit for said element, a low resistance shunt for said element controlled by said room thermostat and opened by the latter on rising room temperature shortly before the room thermostat stops said motor, whereby the heating element is energized during the latter part of each cycle of operation of the burner to cause said relay to be energized to reverse the action of said valve means and operate the unselected nozzle.

6. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump, a circuit for controlling said motor including a bi-metallic thermostat blade switch having an electric heating coil and two contacts and being movable in response to the temperature in the space to be heated to engage both

75 heating coil.

contacts and close said circuit to start the motor, said circuit having one branch which includes said heating coil and another and low resistance branch which includes one of said contacts and which shunts out the first branch, said blade on rising temperature disengaging first from the last-named contact to break said shunt branch and allow the heating coil to be energized to heat the blade, the latter subsequently disengaging from the other contact to stop the motor, ignition means for igniting the air and oil mixture, electromagnetically-operated valve means for selectively connecting said oil conduits to said pump, and a selector switch in circuit with such means and movable from one position to another to cause the connection of one or the other of said oil conduits to the pump; switching means in circuit with the selector switch and electromagnetically-operated valve means and movable from a normal position to a second position to cause a reversal of action of said means, whereby the oil conduit and nozzle not selected by the selector switch is connected to the pump in place of the selected oil conduit and nozzle, and electrical means in series with the heating coil in said second-named branch of the motor control circuit and operable when energized and deenergized to cause said switching means to be moved to its second position and normal position respectively.

7. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump, a circuit for controlling said motor including a bi-metallic thermostat blade switch having an electric heating coil and two contacts and being movable in response to the temperature in the space to be heated to engage both contacts and close said circuit to start the motor, said circuit having one branch which includes said heating coil and another and low resistance branch which includes one of said contacts and which shunts out the first branch, said blade on rising temperature disengaging first from the last-named contact to break said shunt branch and allow the heating coil to be energized to heat the blade, the latter subsequently disengaging from the other contact to stop the motor, ignition means for igniting the air and oil mixture, electromagnetically-operated valve means for selectively connecting said oil conduits to said pump, and a selector switch in circuit with such means and movable from one position to another to cause the connection of one or the other of said oil conduits to the pump; switching means in circuit with the selector switch and electromagnetically-operated valve means and movable from a normal position to a second position to cause a reversal of action of said means, whereby the oil conduit and nozzle not selected by the selector switch is connected to the pump in place of the selected oil conduit and nozzle, and an electric heating coil in series with the first-named heating coil in the second-named branch of the motor control circuit, an electromagnet operable when energized and deenergized to move said switching means to its second position and normal position respectively, and a switch heat-actuated to closed position by the second-named heating coil and when closed connecting said electromagnet in parallel with the second-named

8. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump and adapted to be started and stopped by a room thermostat switch to produce a cycle of operation of the burner, ignition means for igniting the air and oil mixture, valves one for each oil conduit for controlling the connection of the latter to said pump, electromagnets one for each valve each operable when energized to open its valve, energizing circuits one for each electromagnet, and a selector switch operable to close one or the other of said circuits; reversing switch means in said circuits operable when moved from a normal to a second position to open whichever energizing circuit was closed by the selector switch and close the other energizing circuit, whereby the nozzle not selected by the selector switch may be operated, an electromagnet operable when energized and deenergized to move the reversing switch to its second position and normal position respectively, and a circuit for the last-named electromagnet adapted to be controlled by the room thermostat switch and energized for a brief interval just prior to the opening of such switch to stop the burner.

9. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump and adapted to be started and stopped by a room thermostat switch to produce a cycle of operation of the burner, ignition means for igniting the air and oil mixture, valves one for each oil conduit for controlling the connection of the latter to said pump, electromagnets one for each valve each operable when energized to open its valve, energizing circuits one for each electromagnet, and a selector switch movable from one position to another to connect one or the other of said circuits to a source of supply; a reversing switch in each circuit movable from a normal position in which it is closed in its circuit to a second position to break its own circuit and close the other energizing circuit, whereby the nozzle not selected by the selector switch may be operated, an electromagnet operable when energized and deenergized to respectively move the reversing switch to its second and to its normal position, and a circuit for the last-named electromagnet adapted to be controlled

by the room thermostat switch to energize such electromagnet for a brief interval just prior to the opening of said switch to stop the burner.

10. In a dual nozzle oil burner apparatus, which includes a fan and pump for respectively supplying air to an air conduit and oil to one or the other of two oil conduits, each of which terminates in the air conduit with an atomizing nozzle, an electric motor for driving the fan and pump and adapted to be started and stopped by a room thermostat switch to produce a cycle of operation of the burner, ignition means for igniting the air and oil mixture, valves one for each oil conduit for controlling the connection of the latter to said pump, electromagnets one for each valve each operable when energized to open its valve, energizing circuits one for each electromagnet, and a selector switch movable from one position to another to connect one or the other of said circuits to a source of supply; a reversing means in each circuit movable from a normal position in which it is closed in its circuit to a second position to break its own circuit and close the other energizing circuit, whereby the nozzle not selected by the selector switch may be operated, an electromagnet operable when energized and deenergized to respectively move the reversing switch to its second and to its normal position, a circuit for the last-named electromagnet adapted to be controlled by the room thermostat switch to energize such electromagnet for a brief interval just prior to the opening of said switch to stop the burner, a second reversing switch in each of said energizing circuits operable in a predetermined time after the burner is started to move from a normal closed position in its energizing circuit to a second position in which it opens its own energizing circuit and closes the other energizing circuit, and means responsive to combustion at the burner for preventing movement of the second reversing switches from their normal positions.
